(57) **CLAIM**

The ornamental design for a tent, as shown and described.

DESCRIPTION

FIG. 1 is a perspective view of a tent showing my new design; FIG. 2 is a top plan view thereof;

FIG. 3 is a right side elevational view thereof, with a left side elevational view being a mirror image thereof, and,

FIG. 4 is a front elevational view thereof, with a rear elevational view being a mirror image thereof.

The dash-dot broken lines immediately adjacent the shaded areas represent the bounds of the claim and all other broken lines represent unclaimed portions of the design. None of the broken lines form a part of the claimed design.
